GARMENT HANGER

Joseph F. Appleman, Chicago, Ill.

Application January 15, 1946; Serial No. 641,289

7 Claims. (Cl. 223—90)

1

This invention relates to improvements in garment hangers, and more particularly, to the type of hanger described and claimed in my pending application for Letters Patent, Serial No. 622,243, filed October 15, 1945, which resulted in U. S. Patent No. 2,426,292 issued August 26, 1947.

The invention has for its principal desiderata to provide a hanger for coats, skirts, trousers and various other articles of wearing apparel which, by reason of its meritorious and novel construction, will simultaneously support bifurcated or skirted apparel and other body garments, such as coats, cloaks, overcoats or the like in proper form, and so, prevent wrinkling and/or mis-shaping of the same during their hanging; moreover, to prevent undesirable relative shifting of the hanger engaged and supported garments, as by reason of movement of the hanger upon, along or from and to its supporting medium.

It is a further and equally important object of the invention to provide a garment hanger of the indicated character whose over-all length may be selectively adjusted whereby to effect a properly snug fitting and/or engagement of a cloak, coat or similar body garment therewith, the length adjustment of the hanger being accomplished by the operation of a simple though positive means provided to the shoulder engaging and receiving portions of the hanger for automatically imparting longitudinal movement in opposite directions thereto without disturbing or otherwise detrimentally affecting their proper and operative assembly.

The invention also aims to provide a garment hanger in which the relatively opposed companion sections of its assembly will be possessed of a maximum of stress resistance properties, i. e., resistance to stresses which may and will be applied thereto by garments engaged and supported upon it, as well as those to which the device will be subjected during over-all handling and use of the same.

The foregoing, as well as other objects, advantages and meritorious teachings of the invention, will be in part obvious and in part pointed out in the following detailed disclosure thereof, when taken in conjunction with the accompanying drawings, it being understood that the particular form of the invention presented herein is a precise and what is now considered to be the best mode of embodying its principles, but that modifications and changes may be made in specific embodiments, without departing from its essential features:

In the drawings:

Figure 1 is a perspective view of a coat hanger constructed in accordance with my invention.

Figure 2 is a top plan view of the same.

Figure 3 is a fragmentary top plan view of the hanger with a portion of the same broken away.

2

and shown in section to illustrate the means for and the manner in which longitudinal adjusting movement is imparted to the hanger shoulder engaging members.

Figure 4 is a fragmentary side elevation of the improved hanger in which the means for transmitting movement to the hanger shoulder engaging members is shown with the pinion provided thereto and the rack tooth provided portions of said members shown in dotted lines.

Figure 5 is a transverse section taken on the line 5—5 of Figure 4, looking in the direction in which the arrows point.

Figure 6 is a horizontal section taken through the shoulder engaging member retaining sleeve illustrating the adjacent ends of said members in partially distended positions and also illustrating, in dotted lines, the formation of the adjacent inner ends of said members and the pinion for transmitting motion thereto.

Figure 7 is a fragmentary edge or side view of an inner end portion of one of the shoulder engaging members showing its formation and the manner in which rack teeth are provided to the same, and

Figure 8 is a fragmentary detail in plan of the inner end portion of one of the shoulder engaging members.

Referring in detail to the construction illus-

trated by the drawings, the improved garment hanger consists of a pair of longitudinally opposed and aligned garment shoulder engaging and supporting members 1 and 2, each of which is slopingly curved throughout its length and has a transversely convex outer surface and outer end portion whereby to render it more or less shape conforming to adjacent portions of a body garment (cloak, coat, overcoat, etc.) engaged with and supported on the same. The inner and normally lower end portions of the members 1 and 2, while being formed with transversely convex outer surfaces, as above described, are substan-

tially straight and in parallel relationship to the outer or upper portions thereof, the purpose of which will be hereinafter described. Each there-

of is formed with width reduced complementary portions 3 and 4 arranged in juxtaposition, as shown in Figure 1 of the drawings. The inner sides of these complementary portions 3 and 4, i. e., those sides which are adjacent each other, are straight and relatively parallel and have correspondingly formed longitudinal channels therein, in which transversely disposed integral rack teeth 5 are arranged. The upper flange-like sides 6 of

said reduced portions 3 and 4, that is, the flange-like sides above their respective longitudinal channels, are straight-edged and are adapted to be abuttingly engaged, as well shown in Figure 5 of the accompanying drawings. The lower flanged or flange-like sides of each of said portions 3 and 4,

indicated for clarity by the numeral 7, are straight edged but are of less width than the upper flanged sides 6. Thus, it will be seen that the resultant spacing of the sides 7, upon assembly and juxtapositioning of the portions 3 and 4 of the supporting members 1 and 2, provides a longitudinal way between the inner and straight faces of said reduced end portions 3 and 4, the purpose of which will be hereinafter apparent.

The outer and downwardly disposed ends of the supporting members 1 and 2 are each formed with downwardly disposed sides or extensions 8, whose outer surfaces are transversely convex to conform with the adjacent portions of the convex surfaces of said supporting members. Inwardly disposed extensions or arms 9 and 10 are integral with each of the said sides 8 and have their free portions longitudinally bifurcated, as indicated at 11. These bifurcated portions of the extensions 9 and 10, as shown in Figures 1, 2 and 5 of the drawings, are juxtaposed and are arranged in the same plane; moreover, said extensions are disposed substantially parallel to the straight edge inner portions 3 and 4 of the members 1 and 2.

To strengthen or reinforce the bifurcated extensions 9 and 10, I may and preferably do form bracing webs 12 integral with adjacent portions of the outer ends of the supporting members 1 and 2, their respective sides or extensions 8, and their respective inwardly disposed bifurcated extensions 9 and 10.

Because of the formation and relative disposition of the width reduced bifurcated extensions or arms 9 and 10, it will be seen, upon reference to Fig. 1 of the accompanying drawings, that such arms, with the assembling of their respective supporting members 1 and 2, will be arranged in relatively longitudinally opposed juxtaposition; also, that because of the reduced width of said bifurcated extensions, they will be arranged in more or less nested relationship. The respective length of each of the bifurcated extensions or arms 9 and 10, is such that spacing will be normally effected between their open outer ends and the adjacent basal portions of the opposed extensions. Consequently, the insertion and engagement of garments, as for example, trouser legs or cuffs, and skirt waist bands, etc., into and longitudinally of the ways of the bifurcated arms 9 and 10, will be facilitated.

An inwardly-extending lug 13 is integral with or otherwise fixedly mounted upon the inner side of each of the bifurcated arms 9 and 10, somewhat in proximity to the respective outer ends thereof. Consequently, with opposed longitudinal movement of the supporting members 1 and 2 in directions to increase the over-all length of the improved hanger, said lugs will interengage, and so, limit the extent of outward adjusting longitudinal movement of the supporting members.

In order that longitudinal movement in opposite directions may be selectively imparted to the supporting members 1 and 2, the device is provided with a handle or knob 14 mounting thereon a shaft 15, the inner end of which fixedly carries a gear 16 positioned between the rack teeth 5, hereinabove described, provided on the inner straight sides of the reduced complementary portions 3 and 4 of the members 1 and 2, respectively. The diameter of the gear 16 is such as to effect a positive meshing of its teeth with the aforesaid rack teeth 5 on the opposite faces of the reduced portions 3 and 4.

A retaining sleeve, made of metal or other suitable material, and herein indicated by the numer-

al 17, is snugly engaged transversely about the intermediate portion of the hanger construction or assembly, to wit, over and about the reduced complementary portions 3 and 4, hereinbefore described. The normally lower or under side of the sleeve is provided with an opening (see Figure 5) through which the stub shaft 15 passes into the way afforded by the relatively spaced flange-like sides 7. At this point, it will be noted that the length of the stub shaft 15 is such that the knob or handle 14 will have its inner side directly adjacent the corresponding portions of the outer face of the sleeve 17.

A hook or hanger fixture 18, having a right angularly disposed basal portion 18', is arranged upon the normally upper or outer side of the sleeve 17, intermediate its ends, and is secured thereto by welding or other suitable means. Thus, the hanger is provided with a device whereby it may be attached to and supported from a suitable supporting means or object, as for example, a bar, rod, etc.

As above inferred, the length and width of the retaining sleeve 17 is such that it effects a comparatively snug engagement about and with the relatively straight reduced complementary portions 3 and 4 of the supporting members 1 and 2, also, its cross-sectional shape substantially corresponds with that of said complementary portions 3 and 4, as will be recognized upon reference to the Figures 1 and 5 of the accompanying drawings.

In usage of my improved hanger, a body garment, such for example, as a cloak, coat, overcoat or the like, has its shoulder engaging portions 35 engaged with and over the supporting members 1 and 2 in the usual manner. If necessary to adjust the over-all length of the hanger assembly (the supporting members 1 and 2) whereby to properly fit or size the same with relation to the body garment to be supported therefrom, the user 40 of the device engages the knob or handle 14 and rotates it in the required direction. Such rotation will, of course, effect corresponding rotation of the gear 16 whose teeth are enmeshed with the 45 teeth of the several rack portions 5, aforesaid, causing the complementary portions 3 and 4 carrying such racks, to be selectively moved either inwardly or outwardly in opposed directions. The meshing engagement between the teeth of the 50 racks 5 and the gear 16 is sufficiently free of "play" to insure retention of the thus longitudinally length adjusted hanger assembly in an adjusted position.

The hanger, engaged with a body garment, as 55 above, is adapted to be engaged with or supported from a suitable supporting medium and, by reason of the flange formation of the hook 18, it will be seen that pendulous or swinging movement of the hanger in a direction at right angles to the longitudinal axis of the particularly adjacent supporting medium will be prevented. Thereby, shifting or undesirable displacement of the garment hanger engaged and supported garment will be reduced to a minimum, if not prevented.

Excessive outward longitudinal movement or adjustment of the supporting members 1 and 2 of the hanger assembly will be positively prevented by reason of the fact that when the limits of such adjustment movement have been reached, 60 the stops 13 carried by the inner sides of the reduced portions of the bifurcated arms 9 and 10 will become interengaged, and accordingly, will prevent further rotation of the stub shaft 15 with its gear 16 and handle 14, in that particular direction. Limitation of relatively inward longi-

tudinal movement of the supporting members 1 and 2 of the hanger assembly will, of course, be effected when the inner end or shoulder portions of the racks 5 on the reduced complementary portions 3 and 4 of said members 1 and 2 become engaged or contacted with adjacent portions of the gear 16 during its rotary movement.

To support skirts, trousers or other characters of articles of wearing apparel, i. e., bifurcated or skirted apparel, upon the improved hanger, appropriate portions of the same are slidably introduced into the reduced bifurcated portions of the arms 9 and 10, allowing the thus engaged garment to be hangingly supported therefrom with the bifurcated arm engaged portions of the same in a substantially horizontal plane, whereby to ensure their retention in a manner free of wrinkles or similar undesirably distorted conditions.

While I have herein disclosed and described with some particular degree of particularity, my improved garment hanger as being provided with the relatively opposed and horizontally positioned reduced bifurcated arms 9 and 10, it is to be understood that these latter devices may, if desired, be eliminated from the construction, hence, providing a garment hanger including only the aforesaid supporting members 1 and 2. It is also equally apparent that, if desired, but a single bifurcated supporting arm 9 or 10 may be supplied to the hanger assembly construction. That is to say, if desired, only one of the outer ends of the supporting members 1 and 2 may be provided or equipped with the inwardly disposed and normally horizontally positioned reduced bifurcated arm 9 or 10, the length of which may be either increased or decreased from that shown in Figure 1 of the accompanying drawings, to such extent as conditions or preference may dictate.

In constructing the garment shoulder engaging supporting members 1 and 2. I am particularly desirous that the widths thereof shall be sufficient to effect a maxim of contact area with the particular garments to be engaged thereby. In this way, it will be obvious that the shoulder portions of the supported garment will be accorded supporting engagement or contact which is much of the same order or character as that which will be had by the same when engaged with and over the shoulders of a person or wearer. And because of this latter manner of increased area engagement and resultantly increased area support, it follows that the body garment supported upon the members 1 and 2 of my improved hanger will be maintained in natural and proper shape over a prolonged period of time, hence, materially improving their retention in or preservation in proper formation—free of wrinkles and other undesirable distortions. Moreover, because of the transverse convexing of the outer or upper sides of the supporting members 1 and 2 and their ends 8, the immediately above indicated desirable results are more positively assured of attainment. Also, it is to be understood that because of the straight formation of the reduced inner end portions 3 and 4 of the shoulder engaging and supporting members 1 and 2, engagement of the retaining sleeve 17 over and about the same whereby to effectually slidably receive and support them, will be effected, thus causing the relatively oppositely disposed inwardly extending bifurcated arms 9 and 10, to be, at all times, supported or retained in horizontal relationship to the supporting members 1 and 2, and particularly, with relation to their straight com-

plemental end portions 3 and 4. Such retention of the bifurcated arms 9 and 10 in the aforesaid horizontal positions or planes will ensure proper or perpendicular hanging of garments therefrom.

5 I claim:

1. A garment hanger, comprising longitudinally opposed and aligned garment shoulder engaging and supporting members having the adjacent end portions thereof reduced in width and arranged in juxtaposed lateral relation, retaining means engaged about and slidably supporting said reduced and juxtaposed end portions, and means positioned between the adjacent sides of said reduced and juxtaposed end portions operable from without the retaining means to transmit longitudinal motion in opposite directions to the same and to their respective aligned garment shoulder engaging and supporting members.

20 2. A garment hanger, comprising longitudinally opposed and aligned garment shoulder engaging and supporting members having the adjacent end portions thereof reduced in width and arranged in juxtaposed lateral relation, means engaged about and slidably retaining said reduced and juxtaposed end portions, and means carried by said retaining means engaged between and with the adjacent sides of said reduced juxtaposed end portions operable to transmit longitudinal motion in opposite directions to the same and to their respective aligned garment shoulder engaging and supporting members.

25 3. A garment hanger, comprising longitudinally opposed and aligned garment shoulder engaging and supporting members having the adjacent end portions thereof reduced in width and arranged in juxtaposed lateral relation, the adjacent sides of said reduced end portions having longitudinally disposed teeth thereon

30 40 throughout their respective lengths, retaining means engaged about said reduced and juxtaposed end portions slidably supporting the same, and toothed means engaged between and with the teeth on the adjacent sides of said reduced and juxtaposed end portions operable to transmit longitudinal motion in opposite directions to the same and to their respective aligned garment shoulder engaging and supporting members.

45 4. A garment hanger, comprising longitudinally opposed and aligned garment shoulder engaging and supporting members having the adjacent end portions of the same arranged in juxtaposed lateral relation, retaining means engaged about said juxtaposed end portions slidably receiving the same, means positioned between adjacent portions of said juxtaposed end portions operable to transmit longitudinal motion in opposite directions to the same and to their respective aligned garment shoulder engaging and supporting members, and relatively inwardly disposed horizontally positioned bifurcated arms fixedly carried on the outer portions of each of said members in substantially parallel relationship thereto.

50 5. A garment hanger, comprising longitudinally opposed and aligned garment shoulder engaging and supporting members having the adjacent end portions thereof arranged in juxtaposed lateral relation, retaining means engaged about said juxtaposed end portions slidably supporting the same, means positioned between adjacent portions of said juxtaposed end portions operable to transmit longitudinal motion in opposite directions to the same and to their respective aligned garment shoulder engaging and support-

ing members, inwardly disposed and substantially horizontally arranged bifurcated arms fixedly carried on the outer portions of each of said shoulder engaging and supporting members; said arms being substantially relatively parallel and laterally juxtaposed and having their free ends normally spaced from the outer end of the opposite shoulder engaging and supporting members, the combined widths of said arms substantially corresponding with the width of each of said shoulder engaging and supporting members and means on portions of said bifurcated arms interengagable at times whereby to limit outward longitudinal movement of said shoulder engaging and supporting members.

6. A garment hanger, comprising longitudinally opposed and aligned garment shoulder engaging and supporting members having the adjacent end portions thereof arranged in juxtaposed horizontal and laterally overlapping relation, the adjacent sides of said reduced portions having longitudinally disposed and relatively parallel channels formed therein, retaining means engaged over and about said reduced end portions slidably supporting the same therein, and rotatable means positioned between said adjacent sides of said reduced end portions engaged in the channels formed therein and with the inner walls of each thereof operable to transmit longitudinal motion in opposite directions to said opposed and aligned shoulder engaging and supporting members.

7. A garment hanger, comprising longitudi-

nally opposed and aligned garment shoulder engaging and supporting members having the adjacent inner end portions thereof arranged in juxtaposed horizontal and laterally overlapping relation, the adjacent sides of said inner end portions having longitudinally disposed and relatively parallel channels formed therein, retaining means engaged over and about said reduced end portions slidably supporting the same therein, rack teeth on and longitudinally of the inner wall of each of said channels, and a pinion rotatably positioned between said adjacent sides of said inner end portions engaged in said channels and with the rack teeth therein, operable to transmit longitudinal motion in opposite directions to said opposed and aligned shoulder engaging and supporting members.
